TOP-SUPPORTED BEVERAGE DISPENSER

Martelle J. Syverson, Albert Lea, Minn., assignor to
Fountain Industries, Inc., Albert Lea, Minn.

Filed Jan. 6, 1972, Ser. No. 215,987

Term of patent 14 years

Int. Cl. D15—08

U.S. Cl. D94—3 B

FIG. 1

FIG. 2

FIG. 3

FIG. 4

FIG. 5

FIG. 6

FIG. 1 is a frontal perspective view of a top-supported beverage dispenser showing my new design;

FIG. 2 is a top plan view thereof;

FIG. 3 is a frontal elevation view thereof;

FIG. 4 is an elevational view taken from the end as seen from the right of FIG. 3, the opposite end being a mirror image thereof;

FIG. 5 is a rear elevation view thereof;

FIG. 6 is a bottom plan view thereof.

I claim:

The ornamental design for a top-supported beverage dispenser, substantially as shown and described.
